UNITED STATES PATENT OFFICE.

JOSEPH LEA FEARING, OF GREENWICH, CONNECTICUT, ASSIGNEE TO INTERNATIONAL PAPER COMPANY, A CORPORATION OF NEW YORK.

METHOD OF AND MEANS FOR FORMING WATERMARKS IN PAPER.

Application filed November 11, 1895. Serial No. 68,439.

To all whom it may concern:

Be it known that I, JOSEPH L. FEARING, a citizen of the United States, residing at Greenwich, in the county of Fairfield and State of Connecticut, have invented certain new and useful Improvements in Methods of and Means for Forming Watermarks in Paper, of which the following is a specification.

This invention relates to the production of watermarks in paper in the operation of paper making machines, and has for its object the formation of the watermark while the machine is operating at high speed and without the necessity of slowing down the operation as has heretofore been the practice. As far as I am aware, the indenting projections or lines of the watermark formative design have been heretofore arranged on their support, more commonly known as the dandy roll of the paper making machine, without regard to the direction of travel of the pulp layer with which they cooperate in indenting the watermark therein, many, if not the greater number of such projections or lines, extending transversely of the direction of travel. Consequently, with the machine operating at high speed, the pulp would pile up and accumulate on the roll in the angles between the surface of the same and the projections, and, in consequence, would soon obliterate the formative design, and the latter would fail to be impressed in the pulp layer. To avoid this action it has been the custom to slow down the operation of the machine to a rate of travel which would permit the proper indentation of the pulp layer by the formative design without the pulp accumulating and filling in the indenting transverse projections. Such reduction of speed, however, is very undesirable and objectionable as it greatly reduces the capacity of the machine and causes considerable loss in output. To enable the machine to be operated at the high rates of speed now generally adopted, where no formative design is required, and at the same time to provide for the formation of the watermark in the paper, I propose, in accordance with my invention, to arrange the indenting projections of which the watermark formative design is composed, solely, or substantially so, in the direction of travel of the pulp layer, as distinguished from crosswise thereof, with the result that

there will be no opportunity for the pulp to accumulate on or fill in the indenting projections, even under the condition of the maximum speed of operation of the machine, and my invention consists in the improved method of forming the watermark, and in the improved apparatus for carrying said method into effect, which will be fully described in detail in the specification to follow, and the novel features thereof pointed out in the appended claims.

In the accompanying drawings:

Fig. 1 is a side elevation of a portion of the wet end of a Fourdrinier paper making machine, having my invention embodied therein.

Fig. 2 is an elevation on an enlarged scale of the dandy roll removed from the machine, showing my invention applied thereto.

Fig. 3 is a cross section through the same.

Fig. 4 is a view showing a modified form of the invention.

Referring to the drawings:

In the accompanying drawings I have shown the invention applied to the dandy roll of a paper making machine, but it will be understood that the invention is not limited to the dandy roll, but may be applied in connection with other parts of the machine moving in contact with the traveling pulp layer at a point in the machine where the layer is in a condition to be indented by or impressed with the watermark design.

Referring to Fig. 1, the pulp layer 1 supported by the forming wire 2, is advanced by the traveling wire over suction boxes 3 which withdraw the water downwardly from the moist pulp as usual. Cooperating with the traveling pulp layer is a dandy roll 4, formed as usual of heavy wire gauze and mounted by end journals to rotate in contact with the traveling pulp layer so as to smooth down the surface of the same. As best shown in Fig. 2, the roll has applied to its external surface a series of watermark formative designs 5, which designs in the present instance simulate trees, and which are arranged at intervals lengthwise and circumferentially of the roll so as to produce in the paper sheet, corresponding watermark designs at the desired points.

In accordance with my invention the designs 5 are made up of a series of indenting projections 6, in the form of lengths of

slender rods or wires which are soldered or otherwise fastened to the outer side of the roll 4, all of which wires or indenting projections extend circumferentially of the roll ⁵ in the direction of the movement or rotation of the same, and in the direction of the travel of the pulp layer, the said indenting projections in the rotation of the roll in contact with the traveling pulp layer, indenting or compressing the pulp and forming watermarks therein.

Due to the disposition of the indenting projections in the general direction of movement of the roll and of the travel of the ¹⁵ pulp layer, as distinguished from crosswise thereof, there will be no tendency of the pulp to back up and accumulate in the angles between the surface of the roll and indenting projections, and thereby fill up the formative design, even at the highest rate of speed at which paper making machines of the present day are operated, as there will be no projections extending crosswise of the travel of the pulp layer and obstructing the ²⁵ movement of the same as heretofore, and consequently the watermark may be clearly and properly formed in the pulp layer without the necessity of slowing down the operation of the machine.

³⁰ In Fig. 2 the indenting projections or wires 6 are each shown as continuous throughout their length, but this is not necessary for the full realization of all of the benefits and advantages of the invention, as they ³⁵ may be broken or interrupted as shown in Fig. 4; and instead of being straight throughout as shown, they may be wavy or undulating, the important requirement being that, in whatever form the individual ⁴⁰ projections or wires are made, they be so disposed in relation to the travel of the pulp layer, as not to offer sufficient obstruction to the movement of the pulp to cause the latter to lodge in or fill up the formative design and thereby obliterate the same.

It will be understood that the invention is not limited to a formative design of the particular configuration illustrated, as that shown is one selected merely by way of example; and it is manifest that any desired design or configuration may be made up of

formative projections or lines disposed in accordance with the invention as hereinbefore described.

In the foregoing description and accompanying drawings I have set forth my invention in the particular detailed form which I prefer to adopt, but it will be understood that the invention is not limited to any particular form or construction of the parts except in so far as such limitations are specified in the claims.

Having thus described my invention, what I claim is:

1. The method of forming watermarks in paper, which consists in subjecting the traveling pulp layer to the action of indenting projections constituting the watermark formative design and disposed substantially solely in the general direction of the travel ⁶⁵ of the pulp layer.

2. In a paper making machine, the combination of means for supporting the traveling pulp layer, a rotary roll in position to contact with the said layer, and indenting ⁷⁵ projections on said roll constituting the watermark formative design and extending substantially solely in the general direction of the travel of the pulp layer.

3. In a paper making machine, the combination of means for supporting the traveling pulp layer, a rotary dandy roll in position to contact with said layer, and indenting projections on said dandy roll constituting the watermark formative design and extending substantially solely in the general direction ⁸⁵ of the travel of the pulp layer.

4. A watermark forming device for paper making machines comprising a suitable support adapted to move in contact with the pulp layer in the general direction of the travel of the same, and having on the surface thereof indenting projections constituting the watermark formative design, said projections being disposed substantially ⁹⁵ solely in the general direction of the movement of the supporting device and pulp layer.

In testimony whereof, I have affixed my signature hereto.

JOSEPH LEA FEARING.
